UNITED STATES PATENT OFFICE.

WALTER T. PUTNAM, OF NORTH ANDOVER, MASSACHUSETTS, ASSIGNOR TO DAVIS & FURBER MACHINE COMPANY, OF NORTH ANDOVER, MASSACHUSETTS, A CORPORATION OF MASSACHUSETTS.

CARDING MACHINE.

Application filed August 9, 1926. Serial No. 128,062.

This invention relates to means for mounting and adjusting the worker and stripper rolls of a carding machine in proper relation to the card cylinder.

5 In this type of carding machine, well known and familiar to one skilled in this art, the card cylinder is partially surrounded by a plurality of units each comprising a worker roll and a stripper roll. The number of these units varies and it is frequently desirable to be able to change the number of units employed on a given machine.

10 One object of the present invention is to provide a simple and efficient means whereby, either in the assembling of the machine or as required in the subsequent use of the machine, any required number of worker and stripper roll units may readily be mounted in the machine.

15 20 A further object of the invention is to provide a pair of bearing units for each worker and stripper roll unit together with means for securing each such bearing unit in circumferentially adjustable position on 25 the corresponding side arch of the carding machine, thus enabling any required number of worker and stripper roll units to be employed.

These and other objects and features of 30 the invention will appear more fully from the accompanying description and drawings and will be particularly pointed out in the claims.

The drawings illustrate so much of an ordinary type of carding machine as is necessary to a disclosure of the present invention together with a preferred form of construction embodying the said invention.

In the drawings:

40 Fig. 1 is a side elevation, chiefly diagrammatic, of the carding machine.

Fig. 2 is a view in side elevation of a section of one of the side arches illustrating one bearing unit for one unit of worker and stripper rolls embodying the invention.

45 Fig. 3 is a view in cross section taken on the line 3—3 of Fig. 2.

Fig. 4 is a view in cross section taken on the line 4—4 of Fig. 2.

50 Fig. 5 is a view in cross section taken on the line 5—5 of Fig. 2.

An ordinary type of carding machine is shown diagrammatically in Fig. 1 having at

each side a side frame 1 supporting a side arch 2. The main card cylinder 3 is journaled on an axis 4 in the side arches. This cylinder is partially surrounded by a plurality of worker and stripper roll units, the worker rolls being indicated at 5 and the stripper rolls at 6.

55 The outer peripheral face of each side arch is preferably ground or finished off to present a plurality of flat faced concentric ribs 7. Between two of these ribs a T shaped slot 8 is formed extending also concentrically of the side arch.

60 As the construction of the worker and stripper roll journals, the bearing units therefor and the means for adjustably mounting the bearing units and for adjusting the respective journal bearings is preferably the same on both sides of the machine and the same for each unit, it is only necessary to illustrate and describe the construction for one unit.

65 Each bearing unit is shown as comprising a somewhat trapezoidal shaped base plate 9 adapted to seat against the faces of the ribs 7, and preferably provided with a flange 10 overlying the periphery of the side arch. This base plate is provided with one or more bolts, herein shown as two by means of which it is secured in circumferentially adjustable position to the side arch. In the construction illustrated these bolts 11 have 70 their heads 12 seated in the T shaped slot 8 and their stems passing through the base plate and their threaded ends provided with the nuts 13. Thus it will be seen that each base plate is readily positioned and locked 75 or secured in adjusted position of any desired point circumferentially of the side arch.

80 While the T-shaped slot is disclosed as extending throughout the face of the arch, the important feature is that it extends 85 throughout the entire segment of the arch face where the worker and stripper rolls are positioned. Thus in assembling the machine any desired number of worker roll and stripper roll units may be provided and furthermore the number of such units may 90 readily be changed whenever required by any given set of conditions. This standardizes the side arch construction and the 95 construction of the units thus economizing 100 in the manufacture of the machines. This 105

also gives great flexibility to the machine in the hands of the user enabling it to meet varying conditions of use.

In the preferred construction illustrated 5 the base plate 9 at one side is provided with parallel ribs 14 extending parallel to a radius of the side arch. These ribs constitute a guide way. A bearing block 15, recessed from its inner surface at 16 is mounted to 10 slide, on the guide way formed by the ribs 14, radially of the arch. This bearing block at its upper end carries the journal bearing for a worker roll 5. As illustrated the bearing block, for this purpose, is formed into 15 a semi-circular seat 17 in which rests the journal sleeve 18 in which in turn is mounted the journal 19 of the worker roll. Beneath the bearing block a lug 20 projects integrally from the base plate 9. A screw 21 passes through the aperture in this lug and is threaded into the bearing block and 20 is provided with nuts 22 above and below the lug 20. It will thus be seen that by turning the nuts 22 the bearing block may 25 be slid radially on the guide way 14 thus to adjust the journal bearing of the worker roll accurately toward and from the card cylinder but without changing its position circumferentially of the card cylinder and arch.

A bolt 23 is also provided at the upper end of the base plate passing through a radial slot 24 in the bearing block 15 and provided at its outer end with a washer 25, and 35 a nut 26. This bolt, as well as the two nuts 22 provide means for locking the bearing block firmly in its adjusted position.

A second bearing block of generally similar construction to that already described is 40 provided for the journal bearing 28 of the journal 29 of the stripper roll 6. This bearing block is seated upon flat ribs 30 on the base plate. Beneath this bearing block the base plate is provided with another integrally 45 projecting lug 31 and a screw 32 passes through an aperture in this lug, and is threaded into the lower end of the bearing block 27 and is provided with nuts 33 above and below the lug. Thus it will be seen 50 that the bearing block 27 is also adjustable, by a similar means to that already described in a radial direction.

Near its upper edge the base plate 9 is 55 provided with a projecting lug 34 centrally of the ribs 30. Screws 35 are threaded through the side walls of the bearing block 27 and abut this lug 34. Consequently by 60 adjusting these set screws the upper end of the bearing block 27 may be adjusted circumferentially of the arch. This adjustment is comparatively slight and may readily be 65 made by loosening the nuts 33 slightly. This bearing block is also locked in adjusted position not only by the set screws 35 and the 70 nuts 33 but by a bolt 36 passing through

the base plate and passing through an opening 37 in the bearing block and having at the face of the bearing block a washer 38 and nut 39.

It will be seen that the bearing block for 70 the stripper roll journal is adjusted both radially and circumferentially on the base plate and is readily locked in any adjusted position.

When therefore, after the grinding of the 75 worker and stripper rolls, it becomes necessary to readjust the position of these rolls to correct for the grinding operation, it will be seen then that the adjustment provided for the bearing block and the worker roll 80 insures that the axis of the worker roll will always remain in the plane of the axis of the card cylinder while the distance between the surfaces of the worker roll and card cylinder will be accurately determined by 85 this adjustment, while the adjustment provided for the stripper roll enables each journal of the stripper roll to be adjusted toward and from either or both of the surfaces of the card cylinder and worker roll to 90 place the stripper roll in the required co-operative relation with both.

Having thus described the invention, what is claimed as new, and desired to be secured by Letters Patent, is:

1. A carding machine comprising a frame having side arches, a card cylinder journaled in the frame between the arches, a plurality of roll units co-operating with the cylinder in the carding operation and each comprising a worker roll and a stripper roll, a pair of bearing units for each roll unit, each bearing unit comprising a base plate seated against the corresponding side arch face, each side arch having a circumferential way 100 on its face extending continuously throughout the segment for the workers and strippers, and means on each base plate co-operating with the corresponding way for rigidly securing the base plate seated against 105 the side arch at any desired circumferential position throughout said segment, each bearing unit comprising a journal bearing for the worker roll adjustable on the base plate radially of the arch and a journal bearing for the stripper roll adjustable on the base plate radially and circumferentially 110 of the arch.

2. A carding machine comprising a frame having side arches, a card cylinder journaled in the frame between the arches, a plurality of roll units cooperating with the cylinder in the carding operation and each comprising a worker roll and stripper roll, a pair of bearing units for each roll unit, each bearing unit comprising a base plate seated against the corresponding side arch face, each side arch having a circumferential way on its face in the form of a T shaped groove extending continuously 115 120 125 130

around the arch concentric with the axis of the card cylinder, and a bolt passing through each base plate with its head located in the corresponding T shaped groove for rigidly 5 securing the base plate seated against the side arch at any desired circumferential position, each bearing unit comprising a journal bearing for the worker roll adjustable

on the base plate radially of the arch and a journal bearing for the stripper roll adjustable on the base plate radially and circumferentially of the arch. ¹⁰

In testimony whereof, I have signed my name to this specification.

WALTER T. PUTNAM.
